CLAIM

The ornamental design for a coffee table, as shown and described.

DESCRIPTION

FIG. 1 is a front, right and top perspective view of a coffee table, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the coffee table in another state.

The broken lines depict portions of the coffee table that form no part of the claimed design.

1 Claim, 9 Drawing Sheets(56)
